ROLLER MOUNTED VACUUM CLEANER FOR
PROPULSION BY FLEXIBLE HOSE

Edgar P. Senne, Rockville Centre, N. Y.

Application May 22, 1947, Serial No. 749,772

6 Claims. (Cl. 183—37)

1

This invention relates to vacuum cleaners. The present application is a continuation-in-part of my copending application Serial No. 702,389, filed October 10, 1946, now abandoned.

The principal objects of the present invention are to provide a vacuum cleaner (of the flexible hose type) which is compact and easily maneuverable; which will roll easily over floor obstructions; which can be readily pushed, pulled or revolved by manipulation of the hose; which possesses an inherent self-leveling feature cooperative with a particular positioning of the hose attachment fixtures to keep the point of hose attachment approximately in the horizontal plane containing the axis of the wheels; which may in addition possess an electrical switch controlling the motor circuit which is actuated by contact with the floor when the chassis is rocked on its main axis; in which the suction and blowing attachments are located at or about the level of the wheel-axis so that the machine has easy handling characteristics whether it is being used for suction or blowing; in which the heaviest elements of the machine (namely, the motor elements) are positioned immediately below the wheel-axis so as to afford the self-leveling feature; and in which the motor-fan unit is readily accessible for repair without removing it from the chassis.

In the following description, and in the accompanying drawings, there is shown one form of machine embodying the present invention, which has been found to possess the particular advantages pointed out, and is set forth to illustrate the invention. The invention is not, however, confined to any particular detail of form, shape or mechanism, except as pointed out in the annexed claims.

Referring to the annexed drawings which form part of this specification:

Fig. 1 illustrates the operation of raising the hose in order to rock the chassis upon its supporting axis and thus to actuate the switch by contact with the floor.

Fig. 2 illustrates the use of the machine when it is behind the operator and is to be pulled forward by the hose.

Fig. 3 illustrates the use of the machine when it is in front of the operator and is to be rolled backwardly using the hose as a means of transmitting thrust to the machine.

Fig. 4 illustrates the use of the hose to rotate the machine in a horizontal plane (i. e., about axes normal to the floor) by means of a twist of the hose.

2

Fig. 5 is a vertical section through the center of the machine in the plane 5—5 of Fig. 6.

Fig. 6 is a vertical section through the machine in the plane 6—6 of Fig. 5.

5 Fig. 7 is a partial vertical longitudinal elevation, partly in section, of the chassis with one wheel removed, showing the chassis in rocked position when the switch plunger 70 is about to come in contact with the floor.

10 Fig. 8 is a vertical transverse section through the removable intake unit 30 in the plane 8—8 of Fig. 5.

Fig. 9 is similar to Fig. 5, showing the hose attached in the exhaust receptacle so that the machine is suited for use as a blower.

15 This invention relates chiefly to vacuum cleaners of the type often referred to as the flexible-hose type which consists of three principal parts: a cleaning unit 15 which contains the dirt-filtering bag, fan and motor; a flexible hose 57; and a wand 58 usually of steel or other stiff material which has appropriate attachments for suction cleaning or for blowing, spraying, and the like.

20 25 According to one embodiment of the present invention, the cleaning unit consists of a chassis 15, having two large supporting wheels 13 and 14 mounted on the end of a shaft which protrudes on either side of the chassis. These wheels are domed outwardly on either side of the chassis, and the annular shell of the chassis, between the wheels, is correspondingly rounded so that, with the exceptions to be noted below, the entire unit presents the appearance of a sphere. This configuration affords a pleasing appearance. The dome-shaped wheels tend to prevent interference with furniture, rugs and other obstructions.

25 30 35 40 45 50 55 Wheels 13 and 14 have annular rim portions 78 projecting outwardly of the spherical surface and terminating in circular treads 12.

Chassis

The chassis, indicated generally by the reference numeral 15, consists of two flat side plates of circular outline 16 and 17 spaced apart in parallel planes sufficiently to provide space between them for the dirt-filtering bag and the motor-fan unit. The distance between these plates, in the device shown, approximately equals the distance which separates the inner edges of treads 12. The annular edge of each plate extends beyond the shell member 18 (about to be described) and almost, but not quite, to the diameters of the treads 12.

55 A curved shell 18 secured along its edges to

side plates 16 and 17 is suitably shaped according to the spherical outline previously mentioned and with the side plates 16 and 17 forms an enclosure for the chassis 15. Within this enclosure a horizontal separating plate 19 is suitably secured along its edges to the side plates 16, 17 and to the shell 18 in such manner as to divide the enclosed space into upper and lower compartments.

A transverse fixed shaft 20, substantially in the plane of plate 19, passes through side plates 16 and 17 at about the center of each of them. Laterally extending end portions 21 and 22 of shaft 20 provide bearings on which the hubs 23, 24 of wheels 13, 14 are respectively journaled and secured. Preferably the hubs are secured upon these shaft ends by means of screws 25, 26 which may be removed for removal of the wheels.

Separating plate 19 is provided with an upwardly projecting transverse ridge 27 whose lower concave side seats upon shaft 20. This ridge and side plates 16 and 17 transmit the weight of the chassis to the shaft 20 by which it is supported in such manner as to be capable of rocking upon the shaft under the gravitational influences mentioned below.

The enclosed space within shell 18 above separating plate 19 is herein described as the dirt chamber 28. The forward end of this chamber (the left as seen in Fig. 5) provides an opening defined by the inturned edge 29 of shell 18. This opening is adapted to receive a removable intake unit 30 (see Fig. 8). Intake unit 30 is manually removable, and may be locked in place. It serves the dual functions of receiving the locking fixture 11 on the end of the flexible hose 57 and of holding in place, within chamber 28, a dirt-filtering bag. Intake unit 30 is formed of a shell member 31 shaped to conform generally to the spherical outline of the entire device, and a wall member 32 adapted to engage the inturned edge 29 of shell 18. In the lower portion of intake unit 30 is formed a receptacle 33 for receiving (and securing in any known manner) the locking fixture 11. An annular rim 34 secured to wall member 32 provides a recessed annular channel adapted to secure the metallic rim 35 of a dirt-filtering bag 36. Bag 36 is secured to rim 35 in the usual manner. Separating plate 19 is provided with a curved depression 37 adapted to be engaged by the lower part of the rim 35 when the bag is in position.

Intake unit 30 is adapted to be secured in place by means of a locking mechanism operated by a single control lever. This mechanism comprises a locking handle 38 pivoted at 39 and having a wedge-shaped lug 40 (see Fig. 8) adapted to be inserted between the opposed ends of two aligned locking bars 41, 42 slidably secured by screws 43, 44 to one face of wall member 32. The screws pass through slots 45, 46 in bars 41, 42 and sufficient play is provided to permit free movement of bars 41, 42 in a direction transverse to the device as a whole. Springs 47, 48, each secured at one of its ends to wall member 32 and at the other of its ends to bars 41 and 42, urge these bars to move toward each other. When the locking handle is moved (in a clockwise direction as seen in Fig. 5) to the closed position shown in Fig. 5, the pointed end of lug 40 enters between the ends of bars 41 and 42, which are appropriately beveled to facilitate its entrance. In this way locking bars 41, 42 are moved outwardly (see Fig. 8) and their outward extremities penetrate openings 49, 50 in the side plates 16, 17, respectively. Engagement of the ends of bars 41, 42 with the openings 49, 50

75

locks intake unit 30 in the position shown in Fig. 5. Counterclockwise rotation (as seen in Fig. 5) of locking handle 38 about its pivot 39 retracts the nose of lug 40, permits the springs to retract locking bars 41, 42 from engagement with openings 49, 50, and thus frees intake unit 30 for removal from the machine. A spring 51 secured to locking handle 38 and bearing against the inner surface of shell member 31 is reversely curved in such manner as to urge handle 38 either in the direction of its open position as it approaches open position, or in the direction of its closed position as it approaches closed position, or both, thus affording a snap action opposing movement of the handle and securing it in the position to which it is moved.

When it is desired to insert a fresh bag in chamber 28, intake unit 30 is unlocked and manually removed, permitting the old dirt-filled bag to be removed. The rim 35 of this bag is thereupon disengaged from annular rim 34 of the intake unit and the bag is either thrown away (if replacement by a fresh bag is contemplated) or its contents are emptied. Thereupon the metal rim 35 of an empty bag is engaged within annular rim 34 and the bag is reinserted in chamber 28 in such manner that the lower portion of the bag rim 35 is pressed against the wall of the depression 37 in the separating plate 19. Intake unit 30 is then locked in position in the manner indicated.

The lower chamber 60 within chassis 15 beneath separating plate 19 contains a fan 52 and motor 53 of conventional construction. Normally the fan and motor are formed as a single motor-fan unit which is bolted to the flanges of an annular plate 54 secured to separating plate 19 and the lowermost portion of shell 18. Motor-fan unit 52, 53 is arranged to draw air from the rearward end of the chassis (the right-hand end as seen in Fig. 5), and to deliver it towards the front end of the chassis (the left-hand end as seen in Fig. 5). To accommodate the passage of air from the upper to the lower chambers, there is provided a series of holes 55 formed in the separating plate 19 adjacent the intake end of the motor-fan unit. Air propelled by the motor-fan unit leaves the lower chamber as set forth below.

Immediately below receptacle 33 is positioned a second receptacle 100, preferably similar in dimensions with those of receptacle 33, affording an air pathway between the atmosphere and the lower chamber. Receptacle 100 provides the opening through which air propelled by the fan leaves the lower chamber. Receptacle 100 is similarly dimensioned to receptacle 33 in order that locking fixture 11 on the end of the hose may, optionally, be inserted in receptacle 100 if desired. When this is done, the machine is adapted for use as a blower, the filtering bag not being used (being if desired removed). A removable perforated grille 101 is adapted to be seated in receptacle 100 when the hose is not engaged therewith.

Receptacles 33 and 100 are each located as near as may be to that part of the periphery of the chassis which, when the chassis is level (as shown in Fig. 5), is in approximately the horizontal plane which contains the axis of the wheels 13, 14. The purpose of this arrangement is indicated below.

Spanning a cup-shaped depression 61 in the upper surface of shell 18 is a rigid handle 62 suitably curved to conform to the spherical outline of the device as a whole and affording a

means by which the entire cleaning unit may be picked up by hand. The handle is located approximately above the center of gravity of the chassis.

Rotatably-mounted upon one end portion 22 of shaft 20 is a spring-tensioned reel 63 having wound thereon cable 64 which connects motor 53 to a suitable source of power. The free outer end of cable 64 passes outwardly through shell 18 through a hole 65 and is provided with a plug for attachment to an outlet socket. The arrangement is such that tension is exerted on cable 64 tending to reel it up within the machine, so that slack will be taken up. Reel 63 is located externally of the chassis and is concealed within the domed recess adjacent hub 24 of wheel 14.

Accessibility for purposes of repair and adjustment is afforded through the following means. Shaft 20 has an enlarged disc portion 66 integral therewith adapted to be secured by screws 67 to the side plate 16, thus securing shaft 20 against lengthwise displacement and against rotation relative to the chassis. A disc 68, loose upon shaft 20 and preferably secured to side plate 17 serves as a spacer between side plate 17 and reel 63 and provides a key (not shown) furnishing an abutment for the spring which tensions reel 63. Access to the interior of chassis 15 may be had by removing wheels 13 and 14, slipping reel 63 off shaft 20 (after disconnecting the wire connections), and removing the screws 67 which permit shaft 20 to be withdrawn. Thereupon the side plates 16, 17, or either of them, may be removed by removing the screws which secure it to shell 18 and plate 19, and the interior of the chassis is thus laid open at either side for inspection and repair of the parts contained in it, particularly the motor-fan unit, without dismounting these parts from the chassis.

By dividing the chassis into upper and lower compartments, one above the other, and positioning the relatively heavier motor-fan unit in the lower compartment and the relatively lighter dirt-filtering bag in the upper compartment, two effects are achieved. First, the cleaner as a whole is evenly balanced when lifted by the handle 62 and, second, the center of gravity of the chassis is positioned approximately just beneath the shaft 20. These effects are utilized for the purposes described below.

Preferably the motor-fan unit should be so disposed in chamber 60 that the center of gravity of the chassis 15 as a whole is substantially directly below the axis of shaft 20.

Support for the chassis

The projecting ends 21 and 22 of shaft 20 afford, in the specific device here described, the sole means through which chassis 15 rests upon its supporting wheels.

Wheels 13 and 14 consist of hubs 23 and 24, disked spokes 79 suitably curved to conform to the spherical outline, and annular rim portions 78 which extend outwardly beyond the general spherical surface. Curved surfacing material 80 is secured to the outer face of hubs 23, 24, spokes 79 and rims 78 to present a finished appearance, and treads 12 of suitable material, preferably chromium-plated steel, are provided around the wheel peripheries. The radius of wheels 13, 14 is so arranged that the spherical underbelly of chassis 15 is supported clear of the floor by an amount of clearance 74 which is great enough to permit the cleaner to be moved freely over rugs and other minor irregularities and is at the same

time small enough to permit the switch actuating mechanism, below described, to come in contact with the floor when the chassis is rocked about its axis, i. e., shaft 20.

While the support for the chassis here shown consists of two large wheels journaled at their hubs, it is to be understood that other supporting mechanism such as a journaled shaft, rim-journaled wheels or like equivalents may be employed. In general, it is believed, easy maneuverability can be secured, through the use of my invention, when the wheel treads are of large diameter and easily rotatable.

Electrical switching mechanism

Current for the motor 53 is supplied through cable 64 normally wound, as above described, on the spring-held reel 63. The inner end of this cable is connected to the terminals of switch 69, and when this switch is in closed position current is supplied (through circuits not shown) to the motor 53.

Switch 69 (see Figs. 5, 7 and 9) is preferably of the plunger type in which alternate depressions of a plunger 70 against the resistance of a spring (not shown) move the switch contacts to closed position, and intervening depressions of the plunger move the switch contacts to open position. The details of this switch are not shown in the annexed drawings, being of conventional design. The switch is mounted upon a lower portion of shell 18, approximately as shown in Fig. 9. The clearance 74 between the bottom of shell 18 and the floor level when the chassis is balanced in normal or horizontal position as indicated in Fig. 9, and the extent to which plunger 70 normally projects outwardly from the spherical surface of shell 18 when the spring is extended, are so arranged that when the chassis 15 as a whole is rocked about its pivotal point of support (the axis of shaft 20) from the position shown in Fig. 9 to and beyond the position shown in Fig. 7, plunger 70 will come in contact with the floor on which the vacuum cleaner rests, and will thereby be pressed inwardly toward the center of the sphere to an extent sufficient to actuate the switch from open to closed, or from closed to open, position. Thus, each time the chassis is rocked sufficiently to depress plunger 70 by contact with the floor, the switch is actuated and the motor is energized or deenergized.

In order to rock chassis 15, the operator has only to lift the end of flexible hose 57 near to its point of attachment with the machine. By so doing the chassis is tipped from its normal balanced or horizontal position, and as the hose is lifted the plunger 70 is pressed against the floor. One lift of the hose energizes the motor; a succeeding lift deenergizes it.

In my co-pending continuation-in-part application, Ser. No. 67,498, filed December 27, 1948, and entitled Vacuum Cleaner On-and-Off Switching Devices, I disclose and claim broadly mechanisms exemplified by the foregoing for alternately energizing and deenergizing vacuum cleaners of the general character herein disclosed by successive manipulations of the hose away from and return to a predetermined normal operating position to effect switch actuating relative movement of the various machine parts with respect to each other or a floor.

Mode of operation

The manner in which the machine is operated

will now be described with special reference to Figs. 1 to 4.

When the machine is being used to provide suction through hose 51, the locking attachment 11 for the hose is secured within receptacle 33. In the normal balanced position of the machine, indicated in Fig. 5, this receptacle is positioned approximately in the equatorial zone of the chassis. The machine tends to remain in this balanced position by reason of the heavy mass of the motor-fan unit being disposed underneath shaft 20. Any tendency of the chassis to rock from this position is opposed by this mass, which tends constantly to keep the chassis on an even keel. Receptacle 33 is so located with reference to the center of gravity of the machine that receptacle 33 is maintained at or near the horizontal plane containing shaft 20. This position is the one to which I refer as the equatorial position.

Thus, when the hose is attached to receptacle 33, and the operator seeks to maneuver the machine about the floor by pushing, pulling or whirling the hose, the point to which force is thereby applied to the machine tends always to be at approximately the equatorial level of the chassis, about on a level with (but in an axis at right angles to) the main shaft 20.

This relationship produces several functional advantages which are believed not to have been realized in prior machines. When the machine is pushed by means of the hose (see Fig. 3), it does not "roll over" but keeps itself in such position that it receives the thrust imparted to it through the hose at about the level of the shaft, and responds to it by moving along the floor with the chassis remaining level and the wheels revolving in a direction away from the operator. When the machine has come into interference with furniture or rugs, or the hose has become twisted, a quick twirl of the hose by the operator (see Fig. 4) will cause the machine as a whole to pivot on its two wheels (i. e. about axes normal to the floor) so as to resume a position where it can be directly pushed or pulled by the hose, and without tending to roll over on its back. Thus the machine remains highly maneuverable at all times. Also the pickup handle is kept always on top.

Furthermore, the operator is relieved of the necessity of leaning over to operate the switch when it is desired to shut off the motor temporarily. By merely raising the hose (see Fig. 1) the chassis is rocked about shaft 20 till plunger 70 is depressed by contact with the floor and the motor circuit is thereby opened. By repeating this action, the motor circuit is again energized.

The importance of the self-leveling function of the machine, and of the easy-rolling characteristics imparted to it by the two large wheels, is emphasized by the comparatively weak thrust which can be imparted through the hose. The hose used in such machines is characteristically very flexible and possesses little resistance to bending. In order that so flexible a means shall be useful in pushing the machine away from the operator (as shown in Fig. 3) it is essential that the point of attachment of the hose shall not easily rotate to the top of the machine. The self-leveling feature above-described opposes such action.

Further, by locating the receptacle 100 as near as may be in the same equatorial region of the chassis (i. e., close to the horizontal plane which, when the chassis is level, contains the axis on which the wheels are pivoted), the machine is likewise easily responsive and maneuverable when

being used as a blower. In this case, as set forth above, the hose is attached in receptacle 100, the fan exhaust port. By arranging this port, as well, near the equatorial region, the machine can be handled in the same easy fashion when used as a blower.

When the machine is used as a blower, any of the known attachments may be employed on the end of the wand 58. For example, if the blowing is to be utilized for spraying, a suitable spraying attachment 102 may be provided. When the machine is used as a blower, the dirt-filtering bag 28 is preferably removed.

Since the means by which locking fixture 11 may be removably secured within receptacle 33 are well-known, I do not describe them in detail. A similar arrangement is contemplated with respect to receptacle 100.

Angular relationships

Since, as pointed out above, ease of maneuverability is dependent on assuring that the hose will ordinarily be maintained approximately in the equatorial region of the sphere, and this depends on the action of gravity acting upon the center of mass of the apparatus disposed within case 15, it is pointed out as follows:

The center of mass should be a substantial distance removed from the axis of support of the case. The further removed it is, the more pronounced will be the tendency of the case to regain its normal position after being disturbed. Practical limitations of design, however, make it impossible to remove the center of mass more than a few inches below shaft 20. In Fig. 9, the point 105 is assumed to represent the center of mass of the case and contents. This point, when the case has rocked itself to normal position, lies on the radius 104 extending downwardly from shaft 20. Under these conditions a second radius 103 may be regarded as the radius near which (approximately) the hose attachment sockets 33 and 100 lie. A third radius 105 may be regarded as the radius in which the floor-contact switch 69 is positioned. Ideally radii 103 and 104 should be at right angles to each other. Radii 104 and 105 may be at any desired angle, but for greatest convenience should be an acute angle (i. e., less than 90°) and are shown at an angle of approximately 60°. These radii are taken in a plane at right angles to the axis of shaft 20, i. e., the axis of support.

The position of hose attachment sockets 33 and 100 may be varied within a considerable angular range as seen in Fig. 9. Generally speaking, these sockets should be located at a point remote from the vertical plane containing shaft 20 and radius 104. Furthermore, in order to secure maximum ease of maneuverability, the axis of these sockets should be aimed more or less in the direction of shaft 20, and should be approximately midway between the two wheels (see Fig. 1).

Where reference is made herein to a "dirt-filtering bag," it is intended that the reference shall be understood to include bags of any type useful for the purpose, whether of cloth, paper or other material, and, in addition, filtering elements other than true bags which may be suitable for the purpose. The invention is not limited to any particular shape or configuration of parts, nor specifically to the spherical shape of the cleaner unit here shown to illustrate the invention, but is to be taken as including any device embraced within the following claims.

I claim:

1. An air filter machine adapted to be pushed,

pulled or rotated on a floor by manual forces exerted on a flexible cleaning hose, comprising a chassis containing a dirt filter and an air propulsion mechanism for propelling air through said filter, means supporting said chassis clear of a floor for self-leveling rotation about a substantially horizontal axis of rotation, said supporting means including a wheel mechanism adapted to support said chassis for free rolling movement over a floor and for rotation about axes normal to the floor, means on said chassis adapted for the attachment of a flexible hose, said axis of rotation being displaced substantially from the center of gravity of said chassis whereby said chassis will normally assume an equilibrium self-leveling position under the influence of gravitational forces and whereby its stability in such position is sufficient to enable said machine to be pushed and rotated about said axes normal to a floor by manual forces exerted on such a hose without substantial departure of said chassis from said equilibrium position, said means for the attachment of a hose being so positioned that radii drawn from said axis of rotation to said means, and to said center of gravity, are approximately normal to each other whereby pushing forces exerted on such a hose will tend to have a minimum moment of rotation about said axis.

2. An air filter machine adapted to be pushed, pulled or rotated on a floor by manual forces exerted on a flexible cleaning hose, comprising a chassis containing a dirt filter, means supporting said chassis clear of a floor for self-leveling rotation about a substantially horizontal axis of rotation, said supporting means including a wheel and axle mechanism mounted coaxially with said axis of rotation and adapted to support said chassis also for free rolling movement over a floor and for rotation about axes normal to the floor, means on said chassis adapted for the attachment of a flexible hose with one end thereof aligned to direct air to said filter, an air propulsion motor-fan unit located within said chassis below said axis of rotation and of such weight as to place the center of gravity of said chassis substantially away from said axis whereby said chassis will normally assume an equilibrium self-leveling position under the influence of gravitational forces and whereby its stability in such position is sufficient to enable said machine to be pushed and rotated about said axes normal to such a floor by manual forces exerted on said hose without substantial departure of said chassis from said equilibrium position, said means for the attachment of a hose being so positioned that radii drawn from said axis of rotation to said means, and to said center of gravity, are approximately normal to each other whereby pushing forces exerted on such a hose will tend to have a minimum moment of rotation about said axis.

3. An air filter machine adapted to be pushed, pulled or rotated on a floor by manual forces exerted on a flexible cleaning hose, comprising a chassis, means supporting said chassis clear of a floor for self-leveling rotation about a horizontal axis of rotation, said supporting means including an axle and wheels mounted thereon on opposite sides of said chassis and coaxially with said axis of rotation whereby said means are adapted to support said chassis also for free rolling movement over a floor and for rotation about vertical axes normal to said axle, a dirt filter located within said chassis above said axis of rotation, means on said chassis adapted for the attachment of a flexible hose with one end

thereof aligned to direct air to said filter, and an air propulsion motor-fan unit located within said chassis below said axis of rotation and of such weight as to place the center of gravity of said chassis substantially away from said axis whereby said chassis will normally assume an equilibrium self-leveling position under the influence of gravitational forces and whereby its stability in such position is sufficient to enable said machine to be pushed and rotated about said axes normal to said axle by manual forces exerted on such a hose without substantial departure of said chassis from said equilibrium position, said means for the attachment of a hose being so positioned as to be approximately in the horizontal plane containing said axis of rotation when said chassis is in said equilibrium position whereby pushing forces exerted on such a hose in a horizontal direction will tend to have a minimum moment of rotation about said axis.

4. An air filter machine adapted to be pushed, pulled or rotated on a floor by manual forces exerted on a flexible cleaning hose, comprising a chassis containing a dirt filter mechanism and an air propulsion mechanism for propelling air through said filter mechanism, a pair of wheels and an interconnecting axle supporting said chassis clear of a floor for self-leveling rotation about the axle, and means in said machine adapted for the attachment of a flexible hose, the axle being displaced substantially from the center of mass of said chassis whereby the chassis will normally assume an equilibrium self-leveling position under the influence of gravitational forces and whereby its stability in such position is sufficient to enable said machine to be pushed and rotated about a floor by manual forces exerted on such a hose without substantial departure of said chassis from said equilibrium position, said means for the attachment of a hose being positioned substantially in a plane containing the axle, which plane is normal to the plane of the axle and center of mass of the chassis, whereby pushing thrusts on such a hose are applied to said machine substantially only in planes through said axle whereby rotation of said chassis about the axle by said thrusts is minimized.

5. An air filter machine adapted to be pushed, pulled or rotated on a floor by manual forces exerted on a flexible cleaning hose, comprising a chassis containing a dirt filter mechanism, a pair of wheels and an interconnecting axle supporting said chassis clear of a floor for self-leveling rotation about the axle, means in said machine adapted for the attachment of a flexible hose with one end thereof aligned to direct air to said filter mechanism, and an air propulsion motor-fan unit located within said chassis below said axle and of such weight as to place the center of mass of said chassis substantially away from the axle whereby said chassis will normally assume an equilibrium self-leveling position under the influence of gravitational forces and whereby its stability in such position is sufficient to enable said machine to be pushed and rotated about a floor by manual forces exerted on such a hose without substantial departure of said chassis from said equilibrium position, said means for the attachment of a hose being positioned substantially in a plane containing the axle, which plane is normal to the plane of the axle and center of mass of the chassis, whereby pushing thrusts on such a hose are applied to said machine substantially only in planes through said axis whereby rotation of said chassis about the axis is minimized.

said chassis about the axle by said thrusts is minimized.

6. An air filter machine adapted to be pushed, pulled or rotated on a floor by manual forces exerted on a flexible cleaning hose, comprising a chassis, a pair of wheels and an interconnecting axle supporting said chassis clear of a floor for self-leveling rotation about said axle, a dirt filter compartment located within said chassis on one side of said axle, means in said machine adapted for the attachment of a flexible hose with one end thereof aligned to direct air to said filter compartment, and an air propulsion motor-fan unit located within said chassis on the other side of said axle and of such weight that said chassis will normally assume an equilibrium self-leveling position under the influence of gravitational forces in which position the filter compartment is above and the motor-fan unit below the axle, the motor-fan unit also being of such weight that the stability of the chassis in such position is sufficient to enable said machine to be pushed and rotated on a floor by manual forces exerted on such a hose without substantial departure of said chassis from said equilibrium position, said means for the attachment of a hose being positioned substantially in a plane containing the axle, which plane is normal to the plane of the axle and center of gravity of the

chassis, whereby pushing thrusts on such a hose are applied to said machine substantially only in planes through said axis whereby rotation of said chassis about the axle by said thrusts is minimized.

5 EDGAR P. SENNE.
